PAGE 2

Fig. 5.

FIG. 1 is a front elevational view of a cue rack embodying my new design;

FIG. 2 is a side elevational view thereof;

FIG. 3 is a vertical sectional view thereof;

FIG. 4 is a top plan view thereof; and

FIG. 5 is a front perspective view thereof.

The side not shown is substantially the same as that shown in FIG. 2.

The back not shown is substantially plain.

The dominant features of the design are shown in full lines in the drawings.

I claim:

The ornamental design for a cue rack or the like, as shown and described.
